GIB

Anker J. Holter, Brooklyn, N. Y.

Application November 18, 1939, Serial No. 305,206

5 Claims. (Cl. 308—3)

The invention relates to gibbs, particularly such as are used in conjunction with elevators as the guiding means to maintain the proper position of the cage with relation to a rail. The object 5 of the present invention is to overcome certain defects in existing gibbs for the stated purpose and to provide an improved instrumentality which will perform its work more satisfactorily and for longer periods of time.

At the present time it is customary to construct gibbs for elevators in the form of a trough made of wood, Bakelite, hard rubber, malakite, or fibre. Such gibbs are supported and held by a shoe on the elevator and, when new, closely fit 15 the rail along which the elevator moves. As soon as wear sets in it is apparent that the elevator will have more play room, not only in a forward and back direction, but also from side to side, which results in bumps and in uneven progress 20 and in further wear. When the wear becomes sufficiently large, the gib must be replaced.

According to my invention the gib is so constructed that it will fit the rail accurately notwithstanding wear and which need not be replaced, but requires only replacement of the 25 wearing surfaces, which to that end are removably associated with a carrier.

The invention is illustrated in the accompanying drawing in which Fig. 1 is a front face view 30 of the carrier portion of the gib; Fig. 2 is a central longitudinal section of Fig. 1; Fig. 3 is a face view of the three wearing units; Fig. 4 is a section of Fig. 3 on line 4—4; Fig. 5 is a front face view of the completely assembled gib constituted of the parts shown in Figs. 1—4; Fig. 6 35 is an enlarged cross-section on line 6—6 of Fig. 5; and Fig. 7 is an enlarged cross-section on line 7—7 of Fig. 5 with the parts in the positions occupied by them when the gib is associated with 40 its guide rails.

In the drawing, Figs. 6 and 7 show the carrier constructed of three parts, 1, 2, and 3, held together by screws 4. Any suitable material can be used for this carrier such as malakite, wood, 45 fibre, etc. Two sets of such screws 4 are indicated in Fig. 1, but a third set as indicated in Figs. 2 and 7 may be used near the central portion of the length of the carrier trough.

As indicated in Fig. 7, leaf springs 5, 6, and 7, 50 also shown in Fig. 1, are centrally attached to each of the parts 1, 2, and 3 by rivets 8. The ends of the springs 5, 6, and 7 are free and are biased toward the center of the gib. Plates of cast metal babbitt 9, 10, and 11 are then inserted in the carrier trough 1, 2, 3, and due to

the pressure of the springs will occupy a position thereon such as shown in Fig. 6. Each of the metal elements 9, 10, and 11 have stepped contours indicated at 12, 13, and 14 adapted to establish the relative position of the parts shown in 5 Fig. 6 and the relative position of the parts when associated with the elevator guide rail 15 shown in Fig. 7. Each of the castings 9, 10, and 11 are provided with a central counter sink 16 adapted to accommodate the heads of the rivets 8 which 10 extend into the inner portion of the trough formed by the parts 1, 2, and 3. The position of the spring 6 with respect to the carrier is fixed by virtue of rivet 8, and hence the spring cannot get out of position. Although the castings 15 9, 10, and 11 are not secured to the carrier, they are prevented from being longitudinally displaced because the heads of the rivets are seated in the countersinks 16. Thus each rivet 8 holds both its spring and casting in correct 20 position with respect to the carrier, and the casting can be renewed without longitudinally displacing the spring.

The ends of the castings 10 and 11 and of the trough sections 2 and 3 are cut away at 17 as 25 indicated in Figs. 1, 2, 3, and 5 to provide means by which the gib is held in position on the shoe 18 of the elevator. The means for forming this connection are well known and therefore not described. At the ends of the metal parts 9, 10, 30 and 11 some of the material is removed, as indicated at 19, to provide in the assembled condition of the device, an entrance point for lubricants.

As more clearly indicated in Figs. 1 and 2, the 35 parts 1, 2, and 3 of the carrier trough are recessed or rabbeted at 20 to accommodate the springs 5, 6, and 7, respectively, when the parts are in the position shown in Fig. 7.

It will be readily observed from Fig. 7 that 40 when any wear occurs in the metal portions 9, 10, or 11, the springs 5, 6, 7 will preserve a constant position of the plates 9, 10, and 11 with relation to the rail 15, until the gap between the edges of the three plates is completely closed, 45 at which time the babbitt plates should be removed and new plates substituted therefor. The loss of metal due to wear is relatively insignificant and the material of the worn-out plates can be used for casting new plates. The replacement of worn plates by new plates is a matter of extreme simplicity since they merely have to be laid in their intended positions without requiring any mechanical or tool work. Throughout the use of the new gib the elevator will be 55

snugly associated with the guiding rail at all times and will be protected against undue swaying or bumping due to increase (resulting from wear) in the space between the rail and the guiding surfaces with which the rail comes into contact.

Typical dimensions for a gib of the character described are for a $\frac{1}{2}$ inch rail, a width and height of $1\frac{1}{2}$ inches with respect to the trough shown in Figs. 6 and 7 and a length of $8\frac{1}{2}$ inches. The individual sections 1, 2, and 3 of the trough have a thickness of $\frac{1}{4}$ inch. The metal bearing plates 9, 10, and 11 have the same length and thickness as the sections of the trough, the plates 10 and 11, however, having a width of $1\frac{1}{4}$ inches, while the inner plate 9 has a width of $1\frac{1}{8}$ of an inch. The springs 5, 6, 7 are preferably made of steel having dimensions such as $\frac{5}{8}'' \times 6\frac{1}{4}'' \times \frac{3}{16}''$ in the case of the elements 10, 11, and about $\frac{1}{2}'' \times 6\frac{1}{2}'' \times \frac{3}{16}''$ for the end plate 9. There are no projecting parts in the gib and its action in use is that of a positive bearing grip which, notwithstanding wear, still keeps its bearing surface and constantly bears on the rail and is quiet in its action.

Although the new gib has been described with particular reference to its use in connection with an elevator guide rail, it is capable of being used and of functioning in connection with other moving bodies which require a gib to control a relative constancy of position as between the gib and the part with which it is in sliding engagement.

I claim:

1. A guide shoe comprising a gib carrier, a leaf spring, a rivet securing the central portion of said spring to said carrier, said rivet having

a head projecting into the interior of said carrier, and a gib having a countersink mounted within said carrier with said countersink engaging said rivet head.

2. A guide shoe comprising a gib carrier, a leaf spring, means securing said spring within said carrier with the longitudinal length of said spring in approximate parallelism with said carrier, a gib mounted in said carrier and bearing against said spring, and means upon said gib cooperating with said spring securing means for preventing the longitudinal displacement of said gib in said carrier.

3. A guide shoe comprising a gib carrier, a spring, single means securing said spring to said carrier, a gib mounted in said carrier and bearing against said spring, and means upon said gib cooperating with said single spring securing means for preventing the longitudinal displacement in either direction of said gib in said carrier.

4. A guide shoe comprising a gib carrier, a leaf spring, a fastening element securing said leaf spring to the inner wall of said carrier, a gib mounted in said carrier and bearing against said spring, and said element engaging said gib to prevent longitudinal displacement of said gib in said carrier.

5. A guide shoe comprising a gib carrier, a leaf spring, means for securing the approximate center portion of said spring to said carrier, a gib having a bore therein and mounted within said carrier, and said means engaging said bore for preventing longitudinal displacement of said gib in said carrier.
